(57) **CLAIM**

The ornamental design for an analytical instrument, as shown and described.

DESCRIPTION

FIG. 1 is a perspective view of a first embodiment of an analytical instrument showing our new design.

FIG. 2 is a front view of the first embodiment.

FIG. 3 is a back view of the first embodiment.

FIG. 4 is a side view of the first embodiment.

FIG. 5 is a side view of the first embodiment.

FIG. 6 is a top view of the first embodiment.

FIG. 7 is a bottom view of the first embodiment.

FIG. 8 is a perspective view of a second embodiment of an analytical instrument showing our new design.

FIG. 9 is a front view of the second embodiment.

FIG. 10 is a back view of the second embodiment.

FIG. 11 is a side view of the second embodiment.

FIG. 12 is a side view of the second embodiment.

FIG. 13 is a top view of the second embodiment; and,

FIG. 14 is a bottom view of the second embodiment.

The portions of the features depicted in broken lines are not part of the claimed design.

1 Claim, 14 Drawing Sheets
